US00D906250S

(12) **United States Design Patent** (10) **Patent No.:** **US D906,250 S**
Hu (45) **Date of Patent:** **** Dec. 29, 2020**

(54) **CONNECTOR**(71) Applicant: **SZ DJI Technology Co., Ltd.**,
Shenzhen (CN)(72) Inventor: **Dengfeng Hu**, Shenzhen (CN)(73) Assignee: **SZ DJI Technology Co., Ltd.**,
Shenzhen (CN)(***) Term: **15 Years**(21) Appl. No.: **29/736,961**(22) Filed: **Jun. 4, 2020****Related U.S. Application Data**

(63) Continuation of application No. 29/574,358, filed on Aug. 15, 2016, which is a continuation of application No. 29/546,070, filed on Nov. 18, 2015, now abandoned.

Primary Examiner — Angela J Lee*Assistant Examiner* — Shawn T Gingrich(74) *Attorney, Agent, or Firm* — Sterne, Kessler, Goldstein & Fox P.L.L.C.(57) **CLAIM**

The ornamental design for a connector, as shown and described.

DESCRIPTION

FIG. 1 is a top front perspective view of a connector showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the figures show portions of the connector that form no part of the claimed design.
